(57) **CLAIM**

The ornamental design for a battery powered drill with light, as shown and described.

DESCRIPTION

FIG. 1 is an expanded isometric view of the battery powered drill with light showing the design.

FIG. 2 is an assembled isometric view thereof;

FIG. 3 is a top view thereof.

FIG. 4 is a bottom view thereof.

FIG. 5 is a right side elevational view thereof.

FIG. 6 is a left side elevational view thereof.

FIG. 7 is a front elevational view thereof; and,

FIG. 8 is a rear elevational view thereof.
